UNITED STATES PATENT OFFICE.

HENRY C. FORGASON, OF OAKLAND, CALIFORNIA, ASSIGNOR OF ONE-HALF TO H. G. COMSTOCK, OF SAME PLACE.

ELECTRIC-ARC LAMP.

SPECIFICATION forming part of Letters Patent No. 447,767, dated March 10, 1891.

Application filed May 23, 1890. Serial No. 352,886. (No model.)

To all whom it may concern:

Be it known that I, HENRY C. FORGASON, a citizen of the United States, residing in Oakland, in the county of Alameda and State of California, have invented certain new and useful Improvements in Arc Lamps, of which the following is a specification.

My invention relates to electric-arc lamps, my improvement having special reference to the cut-out thereof. The object of my invention is to provide means whereby in a single lamp, when the carbons are exhausted, they will be brought into close contact, thus closing the arc, and when a double-carbon lamp is employed the secondary pair of carbons will do the same.

My invention consists in the construction and combination of parts, as hereinafter described and claimed.

In the accompanying drawing the figure is a front elevation showing my invention complete, and so much of one common form of arc lamp as is necessary to illustrate the connection and operation of my improvements.

A and A' indicate the upper rods of a double-carbon lamp, and C C are the ordinary clamp-rings for lifting them. Details of the connections and means for operating the clamps are omitted, as they form no part of my invention.

Each rod A A' has a reduced portion B B', respectively, at a point which, when the carbons are about exhausted, will arrive at clamp C, and since the clamp C will not then hold the rod the latter will drop and the upper carbon will rest on the lower. Thus in a single arc lamp when the carbons are exhausted the rod will drop and the circuit will be closed through the carbons without the resistance of the arc. In a double-carbon lamp the secondary rod only might have the reduced portion B'. In this case, when the primary carbons are exhausted, the current is transferred to the secondary carbons in the usual manner, and then when the latter are burned out the circuit will be closed by closing the arc; but for a double-carbon lamp I have devised further improvements besides forming reduced portions in both rods. In such lamp if the primary rod A should stick

or otherwise fail to feed the current is transferred to the secondary carbons; but if the primary rod feeds properly it is necessary to provide means to prevent contact of the primary carbons when the reduction B arrives at clamp C, in order that the current may be transferred to the secondary carbons by the ordinary means. If now the secondary rod should fail to feed properly, it is necessary to release the holding means of the primary rod in order to send the current therethrough, and thus relieve the ordinary cut-out as far as possible from danger. I will now proceed to describe these means.

At D is a coarse-wire magnet, the armature E of which is pivoted at F and carries a pawl G. The primary rod A is provided with a recess H at a point, so that as the reduction B arrives at clamp C the said recess arrives opposite the end of pawl G, and the weight of the armature or a spring causes the pawl to enter the recess and prevent rod A from dropping farther.

At I is represented the frame of the working parts, and at L and M binding-posts.

N is the armature, pivoted at n of the cut-out coil P, and is connected to magnet D by wire J, and carries contact-plate o.

K is a plate connected with the magnet D and with the binding-post L. Above plate o is fixed contact O, connected with the coarse-wire coil of magnet P. An adjusting-screw n' is located under armature-lever N.

Q is a fine wire connecting post M with the fine-wire shunt of magnet P, and R is a connection from the metallic frame I to the coarse wire of magnet P.

Of course other parts—such as the upper parts of rods A A' and binding-post M—are insulated from the frame, the current being supplied to the carbon rods in any ordinary manner.

In operation, if the primary rod fails to feed, the current will be, as usual, transferred to the secondary set, and when the latter carbons are exhausted the circuit will be closed through the unburned portions of the carbons, owing to the reduced portions B' allowing rod A' to drop through the clamp, thus closing the arc and allowing the lamp to go out without using the ordinary cut-out at all;

- and the same is true when both sides feed properly, for the primary carbons, when nearly exhausted, are held apart by the pawl G entering recess H, and the secondary side then 5 lights up; but if the secondary side fails to feed it will cut itself out in the ordinary way. This immediately energizes magnet D, owing to the shunt-magnet attracting armature N, closing contacts O o, and the current passing 10 from magnet P through the contacts O o, part of lever N, wire J, magnet D, and the line at binding-post L. The magnet D being thus energized attracts armature E, releases pawl G, and allows the primary rod A to drop and 15 close the circuit through the primary carbons. This immediately relieves the ordinary cut-out; but this, of course, does not occur while the secondary side is in order and burning; but should the necessity arise for the cut-out 20 said cut-out will at once trip the pawl, and thus cut itself out before it has had time to be injured.

To distinguish from the ordinary or present cut-out in use, and which I also use, I 25 term my improvement the "gravity cut-out," among the advantages of which are the following:

- If a lamp is insufficiently trimmed, the 30 gravity cut-out automatically closes the circuit through the arc, thus offering a path of low resistance for the current without danger to the lamp and without loss of energy. If either of the rods stick when the other is consumed, the gravity cut-out closes the arc 35 on the consumed side and prevents the opening of the circuit. If a lamp is left untrimmed, the dynamo may be started and stopped repeatedly without danger to the lamp, for there is no break in the lamp. 40 When lamps are in places inaccessible to the trimmer, as in stores or factories on Sundays while they are closed, the lamps may be left untrimmed for several days without danger, thus saving the lamps and the expense 45 of a pair of carbons.

Small and therefore cheap carbons may be used, especially in all-night lamps during the summer months, for in case they should burn out about daylight the gravity cut-out closes

the circuit and there is no loss but the loss 50 of light for a few minutes.

If a careless trimmer fails to visit a lamp, the gravity cut-out will close the circuit and no loss follows but that of light, which would occur, together with loss of energy and the 55 great liability to burn out the lamp, through defective contacts of the shunt cut-out now in use.

In lamps using the present style of cut-out shunt it often happens that the contact-points 60 are defective, or that there is an unusual mechanical resistance to the armature, which, when the lamp is about exhausted, will cause the arc to blaze, thus injuring the rods and carbon-holders. The gravity cut-out, acting 65 independently of electric control, promptly closes the circuit through the arc and prevents any damage to the lamp or dynamo.

Having thus described my invention, what 70 I claim is—

1. In a double-carbon lamp, the combination, with main and auxiliary cut-outs, of a magnet in the main cut-out circuit, a second magnet for operating the auxiliary cut-out, and a contact operated by the first-mentioned 75 magnet for energizing the second magnet, whereby the main cut-out may be cut out by the auxiliary, substantially as described.

2. In a double-carbon lamp, the combination, with lifting-clamps, of the carbon-carrying rods having reduced portions, one of 8c said rods having also a locking device adapted to be released by magnetic action, substantially as described.

3. In a double-carbon arc lamp, the combination, with lifting-clamps, of the carbon-carrying rods having reduced portions, one of 85 said rods having also a recess, a pawl for engaging said recess, and a magnet in the cut-out circuit for releasing said pawl from 90 the recess, substantially as described.

In witness whereof I have hereunto signed my name in the presence of two subscribing witnesses.

HENRY C. FORGASON.
